A. HUGHES.

CARRIER FOR EGGS, FRUIT, AND THE LIKE.
APPLICATION FILED DEC. 1, 1917.

Patented Dec. 17, 1918.

UNITED STATES PATENT OFFICE.

AGNES HUGHES, OF CINCINNATI, OHIO.

CARRIER FOR EGGS, FRUIT, AND THE LIKE.

1,288,004.

Specification of Letters Patent.

Patented Dec. 17, 1918.

Application filed December 1, 1917. Serial No. 204,865.

To all whom it may concern:

Be it known that I, AGNES HUGHES, a citizen of the United States, residing at Cincinnati, in the county of Hamilton and State 5 of Ohio, have invented certain new and useful Improvements in Carriers for Eggs, Fruit, and the like, of which the following is a specification, reference being had to the accompanying drawings.

10 This invention relates to carriers or cartons for carrying eggs, fruit, candies, electric light bulbs, and other fragile articles, and particularly to those cartons or carriers which are formed of pasteboard to provide 15 a plurality of cells, one for each article to be carried.

The general object of my invention is to provide a light and practical carrier for parcel post or other use, made of pasteboard, 20 which may be very cheaply constructed, which may be shipped in a flat condition and readily formed into condition for use and in which the articles carried are resiliently supported, so that the articles carried 25 will not be crushed or broken.

A further object of the invention is to provide a carton of this character which is particularly adapted for carrying fruit, for the reason that ample ventilation openings 30 are provided, and another object is to so construct these openings that the carton is adapted for carrying eggs and will provide means for candling the eggs, so that the eggs may be examined by the buyer, without removal from the carton, thus doing away 35 with the necessity for the repeated re-handling of the eggs and thus doing away with a very large loss due to breakage in this re-handling operation.

40 A further object is to so form the carton that two longitudinally extending series of compartments are provided, the carton being so formed that these two series of compartments or the walls thereof are yieldingly held in relatively angular relation so that the bottoms of the two compartments are disposed at an obtuse angle to each other, to thereby cause the bottom of the carton to be supported at its outer edges, 45 the pasteboard of which the carton is made yieldingly resisting any force tending to flatten the bottom of the carton, thus providing for a resultant support for the eggs, fruit, or other articles contained within the 50 compartments of the carton.

Other objects will appear in the course of the following description.

My invention is illustrated in the accompanying drawings, wherein:—

Figure 1 is a top plan view of the blank 60 for forming the body of the carrier;

Fig. 2 is a top plan view of the blank for forming the egg tray;

Fig. 3 is a perspective view of the carrier;

Fig. 4 is a transverse sectional view 65 through the carrier on a line cutting one of the locking slots 29 of the tray;

Fig. 5 is a fragmentary perspective view showing the manner in which the top flaps of the half sections interlock with the tray; 70

Fig. 6 is a longitudinal sectional view of the egg tray after the blank is folded; 75

Fig. 7 is an enlarged view of a marginal portion of the blank A showing the locking slots 20; and

Fig. 8 is a fragmentary elevation of the ridge a of the body adjacent one end.

In Figs. 1 and 2, I show fragmentary top plan views of the blanks of which the two sections of the carton are made. The body 80 of the carton is formed from the blank A.

The width of the pasteboard sheet forming this blank is, under normal circumstances, about 16" and may have any desired length, although normally it will have a length of 85 11 $\frac{1}{2}$ ", that is, the length of the completed carton will be 11 $\frac{1}{2}$ ". The outer face of the

carton is lightly scored as at 10 along the middle line of the carton and on each side of this score line 10, there are formed a plurality of substantially oval openings 11 placed at regular distances, there being in an ordinary egg carton, six of these openings on each side of the middle score line 10.

The inner face of the blank is formed with 95 a plurality of relatively light score lines 12 which intersect the openings 11 and extend beyond the adjacent margins of these openings toward the middle score line 10. Punched through the sheet of pasteboard are 100 a series of transversely extending apertures 13 which intersect the middle score line 10, these apertures 13 being disposed on lines extending between the pairs of apertures 11.

Each of these apertures 13 has a relatively 105 contracted middle portion, which widens out to form a triangular end portion.

When the blank is folded upon the score line 10, these apertures 13 form dove-tail shaped slots having contracted throats, the 110

corners of the throats being slightly cut away as at 14 to provide a relatively wide entrance opening. The ends of the blank 5 are provided with the slots 15, each of these slots being substantially angular in form, having arms extending inward, so that when the blank is folded upon the score line 10, angular slots will be provided having relatively enlarged throats, as shown 10 in Fig. 8. About $2\frac{1}{4}$ " from the middle score 10 the inner face of the blank is longitudinally scored as at 16 and about $2\frac{1}{4}$ " outward of the score 16 the inner face of the blank 15 is again scored as at 17 and on a line opposite each pair of openings 11 there are formed openings 18 intersected by the score lines 17, these openings being preferably diamond shaped, the longitudinal axis of each opening being in line with the center 20 of the corresponding pair of openings 11. About $2\frac{1}{4}$ " from the score line 17, the inner face of the blank is scored as at 19. The outer edges or margins of the blank are formed with a plurality of inwardly extending locking notches or slots 20, each of these slots having approximately the form of an isosceles triangle, but having a contracted throat 21 with a flaring mouth 22. It will be noted that these slots 20 on one side are reversely arranged to the slots 20 on the opposite side, that is, that the tongues 23 which form the contracted throats of the slots extend in one direction on the right hand margin of the sheet or 30 blank and in the opposite direction on the left hand margin of the sheet or blank. The lateral margins of the sheet or blank adjacent the ends of the blank are formed with the inwardly extending slots 24. 35 Coacting with the blank A which forms the outer case of the carton is a blank B which forms compartments or walls for the eggs, fruit, etc., this blank also forming a brace for the carton as will be later described. This blank B, as illustrated in 40 Fig. 2, is preferably made of pasteboard and has a length of about 24" and a width of about $8\frac{3}{4}$ ". This blank is formed with a plurality of evenly spaced square openings 45 25, there being slots or notches 26 extending from opposite sides of these square openings and extending in line with the longitudinal axis of the blank. The blank is transversely scored at a plurality of points, as at 27, these scores 27 being formed upon the inner face of the blank and intersecting the openings 25. The outer face of the blank is scored at a plurality of points as at 28, these scores 28 being disposed between the scores 27. On each side of the 50 scores 28 there are formed locking slots 29. This blank is adapted to be folded, as illustrated in Fig. 8, upon the score lines 27 and 28, so that the blank will be approximately zigzag in longitudinal section and, 55

under these circumstances, each pair of slots 29 will register. The extremities of the blank are formed with V-shaped slots 30.

In order to assemble the carton, the blank A is creased upon its middle score line 10, 70 the outside faces of the leaves being disposed toward each other. The blank B is then folded upon the score lines 27 and 28 and the ridge a formed by folding the blank A is inserted in the notches 26 of the folded 75 blank B, the series of double walls formed by folding the blank B being inserted within the slots 13, as illustrated in Fig. 5, the ends of the blank B being engaged in the angular slots 15. It will be seen that when 80 the blank B is thus disposed across the crest a of the folded carton, two longitudinally extending series of compartments will be formed, one series on each side of the crest or double middle wall a, the bottom 85 of each compartment being downwardly curved. Fruit or other articles are now placed in the several compartments, if desired, and the lateral portions of the blank A are folded over. The lateral portions of 90 the blank A are bent upon the score lines 16, 17 and 19, the score lines 16 being coincident with the ends of the compartments b formed by the blank B, the score lines 17 being coincident with the upper corners of 95 these compartments b so as to form top walls and the margins of the blank A outward of the score lines 19 are bent downward in confronting relation to each other and the tongues 23 engage in the locking 100 slots 29, as illustrated in Fig. 5, the slots 24 coacting with the V-shaped slots or notches 30.

When the carton is folded, as above described, there are provided two elongated 105 tubular boxes or containers, each rectangular in cross section, and each divided into compartments, these two boxes being connected by the double dividing wall a and by the folded blank B. It will be noticed that the 110 scores 12 perform a very important function when the box is assembled inasmuch as they cause the bottom of the box to bend in a curve at the corners of each longitudinally extending section of the box so that the 115 bottoms of the longitudinally extending sections extend downward and outward in divergent relation to each other and at an obtuse angle to each other, so that normally the middle of the box will be supported 120 above the table or other support, even when the carton or box is filled with the article and the pasteboard having a certain degree of resilience, these side sections of the box will tend to move so as to shift the bottoms 125 of the longitudinal compartments into this relation. Even if a weight be placed on the top of the box, the curve in the middle of the bottom will cause the box to yield to a certain extent, but will not permit it to 130

flatten out entirely. This gives the box resilience and makes it shock absorbing. Thus the fruit, eggs, etc., supported within the box will be yieldingly or resiliently supported against shock or jar.

It will be seen that the carton thus has a cushioned shock absorbing somewhat resilient bottom and a shape which has the strength of a box or carton rectangular in cross section and a shape which will permit cartons to be disposed one on top of the other or one beside the other. It will further be noted that the inner member B provides a series of curved pockets which adapt themselves to the shape of the articles to be carried, hold the articles in position without any more than a minimum of contact therewith and absorb any shock and, furthermore, that this multi-folded strip or blank B constitutes a brace holding the outer side walls of the box from compression or deformation and also forms part of the locking means for the box holding the outer blank A in its folded and locked position. The notches 20 are so formed as to provide the locking tongues 23 which, when they are inserted into the slots 29 lock the box in its folded position as when these tongues are passed through the slots 29, they overlap each other and the box cannot be unlocked, opened or disturbed by ordinary handling or by turning the box upside down, but can only be opened, without breaking the locking tongues, by pushing the tops of the two sections in opposite directions and it will be noted that thus the cartons are held together or in closed relation, without using paste, string, or any extraneous devices. The openings 11 and 18 provide means whereby the eggs, if eggs are being carried, may be candled. When the diamond shaped openings are placed toward the light, the entire egg can be seen by looking through the corresponding opening 11. These openings also permit the inspection of the contents of the several pockets or compartments and further provide for a perfect ventilation of the carton. It will be noted, of course, that these cartons can be shipped with the blanks laid out flat, thus greatly reducing bulk in shipping.

It will be noted that by the construction which has been described, I provide a box or carrier formed of two relatively elongated half sections joined to each other by a fold forming a median wall and I provide an egg tray disposed within the body and straddling the median wall and formed to provide a series of transversely extending egg pockets and that each half section of the carrier is provided with a top wall having a marginal portion along its inner edge, this marginal portion being bent downward so that the two marginal portions of both sections confront each other and these marginal

portions being formed with interlocking slots to engage with the walls defining the egg pockets. It will likewise be seen that each half section of the carton has a bottom, this bottom extending horizontally inward from the outer vertical wall of the section for a certain distance and then extending upward and inward in a curve and that this curve is secured by scoring the pasteboard of which the bottom is made. Especial attention is called to the means for locking the free margins of the carrier together and to the egg tray as I regard this of particular importance, as it is impossible to release these margins from their engagement with the egg tray without longitudinally shifting the marginal walls of the half sections in opposite directions.

While I have illustrated certain details of construction which I have found to be particularly effective in actual practice, it is obvious that many changes may be made with regard to these details, without departing from the principle of the invention as defined in the appended claims.

Having described my invention, what I claim is:—

1. An egg carrier comprising a body formed of two approximately rectangular half sections joined to each other at their bottom and adapted to be folded together to provide a median upwardly extending wall, the outer walls of the sections extending vertically upward, and then extending inward, and then bent downward into approximate contact with each other, an egg tray extending through said median wall and folded transversely at a plurality of points to provide a plurality of egg pockets, the folds defining the egg pockets extending downward in divergent relation, said median wall being formed with slots to receive the joined walls of the egg pockets, said slots having divergent walls whereby to cause the divergent walls of the egg pockets to interlock with the divergent walls of the corresponding slot.

2. An egg carrier comprising a body having a bottom wall and two vertical side walls, said side walls have portions extending inward to form tops, then extending downward in approximate contact with each other, an egg tray disposed within the body and folded to provide a plurality of egg pockets defined by transversely extending walls, the folds constituting said transversely extending walls being formed with registering slots, the downwardly extending margins of the body being formed with a plurality of slots to receive the transverse pocket walls, each of said slots being formed to provide a tongue having interlocking engagement with corresponding slots in the pocket walls.

3. An egg carrier comprising a body hav-

4

ing a bottom wall and side walls, the side walls having portions extending inward parallel to the bottom and then extending downward in approximate contact with each other, an egg tray disposed within the body and folded to provide a plurality of egg pockets defined by transversely extending walls, the folds constituting said transversely extending walls being formed with registering slots, the downwardly extending margins of the body being formed with slots to receive said walls, the slots in the margins being formed to provide longitudinally extending tongues having interlocking engagement with the slots in the pocket walls, the tongues on one margin extending in opposite direction to the tongues on the opposite margin whereby said margins are engageable with or disengageable from the walls of the egg pockets by movement in relatively opposite directions.

4. A carrier of the character described comprising a body formed of two approximately rectangular half sections, each section having a vertical outside wall and a flat top having downwardly extending marginal portions disposed in approximate contact with each other, each section having a bottom wall extending horizontally inward from the vertical side wall and then extending upward and toward the middle of the body in a curve, said last named portions being joined, the curved portions of the bottom being longitudinally scored and an egg tray disposed within the carrier and engaging the upwardly and medially disposed portions of the body to thereby hold said

portions in approximate contact with each other and prevent lateral spreading.

5. An egg carrier comprising a body 40 formed of two approximately rectangular half sections, the bottom walls of each section extending inward from the side wall thereof and then upward and inward to provide a longitudinally extending median fold, 45 said median fold being slotted at intervals, these slots extending downward, each section having a top wall formed at its margin with a downwardly extending portion, the downwardly extending portions of the two 50 sections when placed together forming a longitudinally extending median wall coacting with the first named median wall, and an egg tray disposed within the body and formed of a strip of material folded upon itself at intervals to provide walls defining a series of pockets, said walls being slotted the tray being longitudinally slotted to receive the median upwardly extending wall 60 of the carrier, the downwardly extending marginal portions of the sections being slotted to receive the walls defining said pockets of the egg tray and having tongues engaging in and interlocking with the slots 65 in said pockets defining walls, the egg tray resting upon the bottoms of the two compartments.

In testimony whereof I hereunto affix my signature in the presence of two witnesses.

AGNES HUGHES.
